UNITED STATES PATENT OFFICE.

ERIC FRITJOF KARLSON, OF BEAUMONT, TEXAS.

POWER-HAMMER.

1,400,166.

Specification of Letters Patent.

Patented Dec. 13, 1921.

Application filed May 13, 1920. Serial No. 381,093.

To all whom it may concern:

Be it known that I, ERIC F. KARLSON, a citizen of Canada, residing at Beaumont, in the county of Jefferson and State of Texas, have invented certain new and useful Improvements in Power-Hammers, of which the following is a specification.

This invention relates to improvements in power hammers. One object is to provide a power hammer adapted to be operated from any power source and adapted particularly for use in small machine shops, blacksmith shops and the like. A further object is to provide a power hammer that can be easily operated by one attendant, that is of few parts and consequently cheap to manufacture. With the foregoing and other objects in view the invention consists in the combination and arrangement of parts to be hereinafter fully described, pointed out in the appended claims and illustrated in the accompanying drawings which form a part of this specification and in which—

Figure 1 is a side elevation of my improved power hammer.

Fig. 2 is a top plan view of the same, enlarged.

Fig. 3 is a fragmentary sectional view of the device.

Fig. 4 is a cross section on line 4—4 of Fig. 1.

Fig. 5 is a view of Fig. 4 in side elevation.

Like reference characters denote corresponding parts throughout the several views.

The reference numeral 1 denotes the shop floor or bed plate of the machine upon which the anvil 2 is arranged, and 3 is a supporting surface for the machine proper. To the supporting surface 3 I secure a casting 4 by the bolts 5 and journaled in said casting and extending longitudinally and approximately centrally thereof is the vertically disposed drive shaft 6 which shaft at its lower end is connected by bevel gears 7 to the power shaft 8. The upper end of said shaft rises above the top of the casting 4 and arranged about said shaft as a center is a ball race 9 for the ball bearings 10 upon which the cam wheel 11 is disposed, the hub of said wheel being fast to the said rotary shaft 6. Adapted to ride upon the cam edge 12 of said cam wheel is a roller 13 carried at the reduced end of the inclined shaft 14 whereby the collar 15 is fixedly secured to the plunger hammer 16 that operates through

guide bearings 17 integral with the said casting 4. As the said cam wheel is rotated by the shaft 6 in the direction denoted by the arrow 18 the roller 13 is picked up by the cam edge 12, at its lowest point, and raised until the highest point of said cam edge is reached from which point the roller and connections are dropped thus permitting the plunger hammer 16 to drop and deliver a blow upon the anvil 2 directly therebelow. The maximum distance of the lower end of the plunger hammer from the anvil is substantially equal to the depth of the cam edge 12 at its highest point. Upon the reduced portion 19 of said plunger hammer an expansion spring 20 is arranged which abuts one guide bearing 17 and the annular shoulder 21 formed upon said plunger hammer by the termination of its reduced portion, said spring serving to accelerate the descent of said plunger hammer and thereby to increase its efficiency. The work under operation is placed upon the anvil 2 and the shaft 6 put in motion when the plunger hammer will be caused to rise and fall successively thereby delivering a series of blows upon the work.

The shaft 6 is formed with a key-way 22, vertically disposed, to receive the key of a cam 23 which rotates with said shaft, said cam being moved longitudinally of said shaft from the position shown in full lines in Fig. 5 to the position shown dotted, or vice versa, through the medium of the inverted U-shaped link 24 which is pivotally connected by bar 25 to the rotary rod 26, that extends through the casting, said rod 26 being oscillated by the bell crank 27. In the position of the bell crank shown in dotted lines in Fig. 5 the cam is raised upon the shaft and in the position shown in full lines the cam is in lowered position and in engagement with the brake rod 28 which is slidably carried by the casting and which carries the brake shoe 29 adapted for frictional engagement with the plunger hammer. A spring 30 arranged upon said brake rod abuts a collar 31, fast upon said rod, and a portion of the casting 4 to yieldingly retain the brake rod in a predetermined position and the brake shoe out of engagement with the said plunger hammer.

The plunger hammer is formed with a notch 32 which, in the raised position of said hammer, is adapted to receive the ex-

treme tip end of a slide block 33 that works in a slot 34 formed in the casting 4 and in one guide bearing 17, said slide block being engaged by a rod 35 which connects it with 5 a piece 36 of the casting, said rod 35 being movable relatively to said piece 36 and a spring 37 encircling said rod and abutting the piece 36 and slide block serving yieldingly to space said members apart. A lever 38 10 also connected to the slide block and fulcrumed upon pin 39 to the casting permits manual control of said slide block, said lever being retained in adjusted position by a catch 40 arranged upon the casting. When the 15 power is shut off and it is desired to retain the hammer in raised position the hammer, while in this position, is engaged by the slide block and descent of the hammer through gravity or expansion of the spring 20 there- 20 by prevented.

The brake rod and connections are not thrown into operation to stop the plunger hammer but merely to soften or lighten its blows. The maximum blow will be struck 25 by the hammer when the brake is in inoperative position. The cam 23 is so positioned upon the shaft 6 that it will cause the brake shoe to grip the plunger hammer immediately after the roller 13 has passed beyond 30 the extreme high point of the cam edge 12.

What is claimed is:—

1. In a power hammer, a casting, a rotary shaft journaled in said casting, a plunger hammer arranged in said casting in 35 spaced parallel relation to said rotary shaft, a cam wheel fast upon one end of said rotary shaft, means connecting said cam wheel and plunger hammer for raising said latter member, said means including a roller adapted 40 to travel over one edge of said cam wheel, and means adapted to frictionally grip said plunger hammer immediately after said roller has passed beyond the extreme high point of said cam wheel.

45 2. In a power hammer, a casting, a rotary shaft journaled in said casting, a plunger hammer arranged in said casting, a cam wheel fast upon one end of said rotary shaft, means connecting said cam wheel and plunger ham- 50 mer for raising said latter member intermittently, said means including a roller adapted to travel over one edge of said cam wheel,

and means adapted for engagement with said plunger hammer immediately after said roller has passed over the extreme high point 55 of said cam wheel whereby the succeeding movement of said plunger hammer is retarded, said means including a brake shoe.

3. In a power hammer, a casting, a rotary shaft journaled in said casting, a plunger hammer arranged in said casting, means connecting said rotary shaft and plunger hammer for alternately raising and releasing said latter member, said means including a roller adapted to travel over one edge of said cam 65 wheel, and means adapted for intermittent engagement with said plunger hammer whereby the velocity of the drop of said hammer is retarded.

4. In a power hammer, a casting, a rotary 70 shaft journaled in said casting, a plunger hammer arranged in said casting, means connecting said rotary shaft and plunger hammer whereby motion is intermittently imparted to said latter member, a brake carried 75 by said casting for releasable engagement with said plunger hammer, brake actuating means arranged upon said rotary shaft, and manually controlled means whereby said brake actuating means may be moved into 80 or out of operative engagement with said brake.

5. In a power hammer, a casting, a rotary shaft journaled in said casting, a plunger hammer arranged in said casting, means 85 connecting said rotary shaft and plunger hammer whereby motion is intermittently imparted to said latter member, a brake carried by said casting for releasable engagement with said plunger hammer, a cam slidably keyed to and rotative with said rotary 90 shaft for disposition in or out of contiguity with said brake, said cam when in contiguity with said brake imparting an intermittent movement thereto, and manually operable 95 means for positioning said cam.

In testimony that I claim the foregoing as my own I have hereto affixed my signature in the presence of two subscribing witnesses.

ERIC FRITJOF KARLSON.
